UNITED STATES PATENT OFFICE.

SHERWOOD B. NORRIS, OF AUBURN, MAINE.

DEVICE FOR OPERATING SWITCHES.

SPECIFICATION forming part of Letters Patent No. 595,197, dated December 7, 1897.

Application filed November 12, 1896. Serial No. 611,873. (No model.)

To all whom it may concern:

Be it known that I, SHERWOOD B. NORRIS, a citizen of the United States of America, residing at Auburn, in the county of Androscoggin and State of Maine, have invented 5 certain new and useful Improvements in Devices for Operating Switches; and I do hereby declare the following to be a full, clear, and exact description of the invention, such as 10 will enable others skilled in the art to which it appertains to make and use the same.

My invention relates to improvements in devices for operating switches for electric-motor cars, and is designed to supply means 15 whereby the motormen may throw the switch from either platform of the car without leaving the platform, and also to do away with the long and clumsy switch-rod.

To this end my invention consists of wedge-shaped wheels pivotally attached to the truck-frame of the car and projecting outwardly therefrom, means for causing said wheels to be forced down and held upon the track, and in certain other details of construction to be hereinafter more fully set forth and described.

In the drawings herewith accompanying and forming a part of this application, Figure 1 is a side elevation of a portion of the car, showing my improved device in position. Fig. 2 is a top plan view of the truck and guard and my switch-thrower, showing the manner in which the wedge-shaped wheels take and throw the switch; and Fig. 3 is a 35 detail view of the switch-thrower.

Same letters refer to like parts.

In said drawings, A represents the body of the car, B the trucks thereof, and C the guard-frame, which generally extends in 40 front of the wheels. Rigidly attached to the front portion of the guard in any suitable manner is an outwardly-projecting frame D, consisting of two members E and F, joined together in any suitable manner, as shown at 45 G in Fig. 1. Said frame is attached to each side of the front portion of the guard. Pivotally mounted in the end of the frame are lever-arms H. Said lever-arms at their free extremities are provided with forked arms 50 h, in which are mounted axles i. Loosely mounted on said axles are wedge-shaped wheels I. Pivotally attached to said lever-

arms H and to the rigid frame D in any suitable manner are toggle-arms J. Attached to said toggle-arms J at the point where they 55 join is a rod K, which extends to the platform of the car. Attached to each platform of the car is an ear L. Pivotally mounted in said ear is a bell-crank lever M. Seated in said platforms in a suitable socket N is a foot-lever O. Said foot-lever O is pivotally connected with one arm of the bell-crank lever, as shown at P, the rod K being attached to the other arm of said bell-crank lever, as shown at P. Attached to the upper member of 60 the frame D is a spiral spring Q. Said spring at its lower end is attached to the lever-arms H and serves to hold said arms normally 65 away from and out of contact with the track. I mount the wedge-shaped wheels I loosely 70 in the forked arms h, in order that they may yield slightly when pressure is brought to bear laterally against them by the switch-guard on the rail, so as not to break or twist the forwardly-extending frame D. To accomplish this, I insert between the inner arms and the wheel of the outer lever-arm a spiral 75 spring R of sufficient tension to allow a slight lateral movement when the wheel is in operation. I surround the axle of the inner arm 80 on the one side with a spiral spring T. Wound on one of the forks is a spring S, the free end being so placed as to press against the side of wheel and keep it normally at or near the middle of the axle, but at the same time 85 it will allow the wheel a slight lateral movement.

It will be seen that when pressure is brought to bear upon the foot-levers and the rods pulled outwardly the wedge-shaped wheels 90 by means of the toggle-joints will be forced downwardly, so that they will bear upon the track with considerable pressure.

It is necessary that there be two sets of these wedge-shaped wheels and their connecting mechanism on each end of the car. The wheel intended to throw the switch from a straight line to a curve is always placed on the outer side, and the one intended to throw the switch from a curve to a straight line is 100 placed on the inner side.

The wheels are made in such a form that its circumference is very sharply pointed and will fit into the space between the switch

tongue and guard when pressure is brought thereon by means of the bell-crank lever and connecting-rod. It will be seen that the wheels, if pressed downwardly into the space 5 between the switch guard and tongue, owing to their wedge formation and sharpened circumference will force the tongue of the switch to one side or the other, as is needed. It is also necessary to provide each platform of the 10 car with two sets of foot-levers for operating my device, for it will be seen that each set of wheels are entirely independent of each and are also operated independently.

The operation of my improved device is as 15 follows: As the car approaches a switch if the motorneer wishes the car to continue on a straight run and the switch is thrown to make the car round a curve he presses on the inner foot-lever. This throws down the 20 inner of the two levers and changes the tongue, so as to allow the car to continue on a straight course. It is this inner wheel which is always used to throw the switch-tongue from a curve to a straight. To allow 25 the car to take a curve, the outer of the two foot-levers is forced downwardly, thereby forcing the outer lever-arm down upon the track. The object of the springs being interposed between the forked arms and the 30 wheel is to compensate for the straight forward movement of the car-body before the trucks take the switch. Were it not for this lateral movement allowed the wedge-shaped wheel the strain on the forwardly-projecting 35 frame would be so great as to either break it from the truck-guard or to wrench it so badly as to make it inoperative. The object of the small spiral spring on the axle of the inner wheel is to allow lateral movement in case 40 the wheel does not on the moment of application strike the crease between the guard-rail and switch-tongue, and also to allow for the rigidity of the switch-guard. Were it not for this movement allowed the wheel it 45 would ride up against the guard and prevent

the said wheel from turning the switch. The small spiral spring on the outer wheel is inserted for the same purpose.

Having thus described my invention and its use, I claim—

In a device for operating switches, in combination, trucks, rigid arms attached thereto and extending outwardly therefrom, said arms being connected at their top and bottom by suitable rods, pairs of lever-arms pivotally connected to said braces at each side and extending rearwardly and diagonally downward, said lever-arms being provided with forked extremities, wedge-shaped wheels adapted to revolve on said axle, springs interposed between the arms of said forked extremities and wedge-shaped wheels and surrounding said axles to allow said wedge-shaped wheels a lateral movement, toggle-joints, one member of which is pivoted at its 65 extremity to the upper portion of said rigid brace, the other member of which is pivoted at its extremity to the lever-arm, rods connecting said toggle-joints and extending to the car-platform, bell-crank levers pivotally mounted on the bottom of the car-platform, foot-levers in connection with and pivotally attached to one of the arms of said bell-crank lever, the other arm of said bell-crank lever being connected with said rods, which, 70 when drawn forward, straighten said toggle-joints and force said wedge-shaped wheels downwardly upon the track, retracting-springs extending from said lever-arms to the upper portion of said rigid brace for the purpose of normally holding said wheels out of engagement with the track, substantially as and for the purposes set forth.

In testimony whereof I affix my signature, in presence of two witnesses, this 7th day of 85 November, A. D. 1896.

SHERWOOD B. NORRIS.
